UNITED STATES PATENT OFFICE.

HORACE B. SETZLER, OF COFFEYVILLE, KANSAS, ASSIGNOR TO THE NATIONAL
REFINING COMPANY, OF CLEVELAND, OHIO, A CORPORATION OF OHIO.

APPARATUS FOR TREATING HYDROCARBON DERIVATIVES.

Application filed January 14, 1918. Serial No. 211,721.

To all whom it may concern:

Be it known that I, HORACE B. SETZLER, a citizen of the United States, residing at Coffeyville, in the county of Montgomery and State of Kansas, have invented certain new and useful Improvements in Apparatus for Treating Hydrocarbon Derivatives, of which the following is a specification.

My invention relates to improvements in apparatus for treating hydrocarbon derivatives; the object thereof being to provide means for use during the process of decomposing hydrocarbons mainly of the paraffine series, in the production of crude gasoline.

15 My apparatus is an improvement upon that already described in my prior applications, Serial Numbers 58,720 and 102,651, and the features of improvement will be more particularly set forth and claimed herein in distinction from my prior applications.

The present apparatus is designed and especially adapted for conducting an economical process for decomposing gas-oil, freeing a minimum amount of carbon and fixed 25 gases therefrom, and producing crude gasoline. This process has as its fundamental feature the separation of all inert hydrocarbons and the elimination of them from the zone of reaction, and in addition the introduction of fresh supplies of hydrocarbons out of contact with the vapors of distillation, for the purpose of avoiding the solution of the hydrocarbons of lower boiling points and their reintroduction to the zone 30 of reaction within the still. Said process is herein adverted to merely for the purpose of illustration, and is more fully described and claimed in my co-pending application, Ser. No. 211,722.

40 My apparatus may be briefly described as consisting of a suitable pressure-distilling apparatus with which is immediately associated a composite initial cooling appliance which I may term a reflux dome and exchanger. This appliance discharges respectively from its two members or limbs directly into the still and into suitable cooling coils under pressure. The supply line for the still is conducted by suitable tubing 45 or pipes through these members, preferably in reversed direction to the flow of the vapors of distillation therethrough and to a point in the still substantially or entirely out of contact with such vapors of distillation, as

beneath the level of the body of hydrocarbons under treatment. 55

The accompanying drawing illustrates said apparatus principally in section but partially broken away and in diagram, whereby I may explain my invention in 60 more detail, as in Fig. 2.

A suitable pressure still *a* is shown at the left-hand portion of the drawing, which is equipped with a rotatable shaft *b* slightly eccentric to the horizontal axis of said still 65 and loosely mounting duplicated helicoidal blades *b'* slightly less than the interior diameter of the still, but so positioned as constantly to scrape the heated bottom sheets of the still. The furnace and its adjuncts are not shown and do not need to be described, nor does the apparatus connected with the pulley wheel *b''* for rotating the shaft. Injecting water pipes *b'''* are provided for cooling the end bearings. Further 70 structural details thereof and of the preferred associated apparatus may be ascertained by making reference to Letters Patent, No. 1,292,966, granted to me January 28th, 1919. 75

Immediately above the still is positioned the reflux dome *d*, which is connected by a pipe *d'* with the adjacent exchanger *e*, and the latter in turn is connected by a pipe *e'* with cooling coils and valved containers for 80 controlling the flow of the condensed products; none of which are involved in the present invention and do not require description. A pump *f* is provided for supplying fresh hydrocarbons under pressure, 85 and suitably metered at *f'* through the supply line *g* and comprising the coils *g', g''* and the inlet pipe *g'''*, which extends below the level of the body of hydrocarbons under treatment within the still. It will be observed that the coils or pipes *g', g''*, are 90 relatively proportioned to secure a reciprocal relative cooling effect within the composite cooling appliance comprising the dome *d* and exchanger *e*. The dome is 95 shown broken away from its connection with the still, merely for the convenience of illustration, but in practice is connected thereto so that the vapors readily pass into the dome and the reflux will flow back to 100 the still, as will be understood by those skilled in the art. Suitable casings *c, c'* and the spaced covering *c''*, respectively, pro-

2
tect the members of the cooling appliance from the immediate action of the external air and the weather, while a thermometer *h* is provided in association with the dome, 5 and another thermometer *i* in association with the still, for the purpose of accurately regulating the respective temperatures. Similarly a pressure gage *j* is provided for accurately indicating the internal still pressure.

10 The still being approximately half filled with gas oil, and suitably heated for the necessary period, until a temperature ranging from 700° F. to 750° F. and a pressure 15 ranging from sixty to one hundred pounds per square inch interiorly, are respectively maintained in said still, the products of decomposition and distillation will commence to pass off through the reflux dome, 20 which is thereby heated and certain portions of the hydrocarbons are thereby reintroduced into the still. It is an ascertained fact, however, that at the range of temperature and pressure above stated and preferred by me in the practice of my process, 25 those hydrocarbons which have boiling points ranging from 310° F. to 575° F., which I may generically term kerosenes, are substantially unchanged at the temperatures within the still and are unaffected for 30 the purpose of decomposing crude gasoline line therefrom. Accordingly, the supply pump *f* is started as soon as the temperature of 550° F. is observed upon the thermometer *h*, and additional hydrocarbons are 35 pumped into the still through the supply line in order that the temperature of the dome shall not be raised above 575° F.

Accordingly, the supply of hydrocarbons 40 is furnished to the still in a preheated condition, and the process is made continuous. Moreover, as the fuel oil is led into the still out of contact with the vaporous products 45 of distillation no solution of the vaporous hydrocarbons of low boiling points will occur, as is the case if the supply of fresh hydrocarbons comes in contact therewith.

It will be understood by those skilled in 50 the art, that the reflux dome, maintained at a temperature to avoid condensing the kerosenes, will accordingly return to the still only those hydrocarbons of higher boiling points, which may be again subjected with advantage to the process of decomposition. 55 The heated vapors, however, in passing through the adjacent exchanger will be materially condensed thereby before reaching the cooling coils, and consequently the oil supply will be furnished to the dome at a 60 correspondingly elevated temperature, so that the elimination of the kerosenes is certain to take place.

Thus a material conservation of heat is

effected, as compared with apparatus where- 65 in water-cooled coils or other external means are employed for condensation. Moreover, the temperature in the dome may be better regulated by the means set forth.

It will be observed that the oil supply is directed from the dome and through the 70 pipe in the upper portion of the still to the left hand lower portion thereof, closely adjacent to the firing chamber. Consequently, the fresh supply of fuel oil or other hydrocarbons under treatment, is raised initially 75 from its pre-heated temperature to the desired distilling temperature.

It is highly desirable in practicing this or analogous processes, that the temperature in the dome should be maintained stationary within narrow limits, and accordingly the provision of a thermometer 80 intimately associated with the dome for indicating the critical temperature, is necessary for securing the best results.

My novel dome and exchanger is shown somewhat in detail as diagrammatically associated with the fragmentary section of a still *a*; which apparatus is well adapted to the practice of the process adverted to 90 and more fully described in my application, Ser. No. 211,722, filed concurrently herewith. The two limbs of the condensing apparatus are connected as indicated in Fig. 1, but the proportioning of the still and pump is shown on reduced scale for the 95 purpose of illustration.

In Fig. 2 the oil level is assumed to be just below the line *x*—*x*, while in practice, the still is connected with the casings *d* and *e* so that the pressure is maintained in common therein.

Having now described the apparatus embodying my invention and, in general, the function thereof, I claim as new and desire 105 to secure by Letters Patent, the following:

In apparatus for treating hydrocarbons, the combination with a pressure still, of a two-limbed condensing apparatus connected directly above the still and discharging 110 from one of its limbs into the same and from the other limb into cooling coils, supply coils positioned within said limbs and a supply line connecting with said coils for furnishing hydrocarbons through the condensing apparatus to said still, whereby the effective temperatures in both limbs may be approximately maintained and waste of heat may be avoided, substantially as set forth.

In testimony whereof I affix my signature in the presence of two witnesses.

HORACE B. SETZLER.
